US00D982599S

(12) **United States Design Patent** (10) Patent No.: **US D982,599 S**
 Scheller et al. (45) Date of Patent: ** Apr. 4, 2023

(54) **DISPLAY SCREEN OR PORTION THEREOF WITH GRAPHICAL USER INTERFACE**

(71) Applicant: **PNC Financial Services Group, Inc.**, Pittsburgh, PA (US)

(72) Inventors: **Jerry Scheller**, Moon Township, PA (US); **Todd Tkach**, Wexford, PA (US); **Urich Bowers**, Bridgeville, PA (US); **Mecal McDade**, New Alexandria, PA (US)

(73) Assignee: **PNC Financial Services Group, Inc.**, Pittsburgh, PA (US)

(**) Term: **15 Years**

(21) Appl. No.: **29/746,337**

(22) Filed: **Aug. 13, 2020**

(51) LOC (14) Cl. **14-04**

(52) U.S. Cl.

USPC **D14/486**

(58) **Field of Classification Search**

USPC D14/485-495

CPC G06F 3/048-04897

(57) **CLAIM**

The ornamental design for a display screen or portion thereof with graphical user interface, as shown and described.

DESCRIPTION

The FIGURE is a front view of the display screen or portion thereof with graphical user interface showing the claimed design.

The outermost broken lines in the FIGURE show a display screen or portion thereof and form no part of the claimed design.

The other broken lines in the FIGURE show portions of the graphical user interface that form no part of the claimed design.

1 Claim, 1 Drawing Sheet
